UNITED STATES PATENT OFFICE.

JOHN A. MORRISON, OF MANSFIELD, OHIO.

LIFTING-JACK.

1,370,344.

Specification of Letters Patent.

Patented Mar. 1, 1921.

Application filed March 29, 1920. Serial No. 369,826.

To all whom it may concern:

Be it known that I, JOHN A. MORRISON, a citizen of the United States, residing at Mansfield, in the county of Richland and State of Ohio, have invented new and useful Lifting-Jacks, of which the following is a specification:

The present invention relates to lifting jacks and more particularly to that type of jack especially adapted for automobile use and has for its objects the provision of a jack having a two part lifting bar, one part thereof being arranged to be raised independently of the other part, until a certain distance is reached, after which the second part of the lifting bar is automatically locked to the first part and moved therewith, thus providing for a wider range of movement than can be obtained with the usual form of lifting jack; other objects of the invention being to provide a construction in which the raising and lowering of the lifting bar is effected by a worm drive, thus permitting the lifting bar to be stopped at any desired elevation as contrasted with the step by step movements which are common in lifting jacks wherein the lifting bar may only be stopped at certain spaced points; other objects being the provision of a lifting jack of the character above briefly described, which is simple and inexpensive to manufacture and durable and efficient in use.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part thereof, in which—

Figure 1 is a front elevation of a jack constructed in accordance with the invention, showing the lifting bar partly raised.

Fig. 2 is a section on the line 2—2, Fig. 1.

Fig. 3 is a side elevation of the jack in the initial position.

Fig. 4 is a section on the line 4—4, Fig. 2.

Fig. 5 is a fragmentary section similar to Fig. 2 showing the worm engaging the second member of the lifting bar.

Fig. 6 is a fragmentary rear elevation of a portion of the standard of the jack showing the locking member which automatically locks the two parts of the lifting bar together.

Fig. 7 is a fragmentary perspective view of a portion of the standard illustrated in Fig. 6, parts being broken away for the purpose of illustration; and

Fig. 8 is a detail perspective view of the locking member which automatically locks the two parts of the lifting bar together. 70

A practical embodiment of the invention is disclosed in the accompanying drawings, forming a part of this specification in which similar numerals of reference indicate corresponding parts throughout the several views. 75

Referring to the construction illustrated in the accompanying drawings, 1 indicates a standard which is of channel form and preferably provided with the integral base 80 2 and the integral bearings 3 at its upper portion.

The side members of the standard are provided with inwardly disposed vertical ribs 4 and the channel worm rack member 5 is mounted for vertical reciprocation within said standard being provided with vertical grooves 6 which receive the ribs 4, vertical ribs 7 being also provided upon said rack member for slidably engaging the grooves 90 8 in the rear portion of the standard. 85

The lifting bar is formed of two independently movable rack portions arranged to be automatically locked together as will be further described and comprises the channel worm rack 5 and the worm rack 9 which is slidably mounted within said channel member, having the vertical flanges 10 which are received within corresponding grooves 11 in the channel rack member, 100 worm teeth 12 being provided upon both of said racks.

A seat or head 13 is preferably provided upon the upper end of the rack member 9 for the purpose of engaging with the object 105 to be lifted. The channel rack member 5 is provided with a vertical groove 14 terminating near its upper portion at the shoulder 15 and a stud 16 is mounted in the lower portion of the rack member 9 and arranged 110

to reciprocate within the groove 14 and engage the shoulder 15 as will be further described.

The locking member 17 is carried by the 5 channel rack member, being located through a suitable aperture 18 therein, a pin 19 being located through said channel member, engaging the locking member between the shoulder 20 and the lugs 21, thus preventing 10 accidental displacement of the locking member. A vertical groove 22 is formed in the inner end of the locking member to allow the pin 16 to pass therethrough.

The outer end of the locking member is 15 reduced as at 23 and provided with the oppositely disposed studs 24 arranged to be normally located within the inclined grooves 25 which are formed in the rear wall of the standard 1, an aperture 26 being formed in 20 said rear wall in order to allow the locking member to project therethrough.

A shaft 27 is journaled within the bearings 3 and a worm 28 is fixedly mounted upon said shaft and normally meshes with 25 the worm rack 9, the worm teeth being cut away from the upper end of the worm rack 5 in order that the worm will not mesh therewith when said rack is in the lowered position.

30 A beveled pinion 29 is fixed upon the lower end of the shaft 27 and meshes with the beveled pinion 30 which is fixedly mounted upon the shaft 31, said shaft being journaled through the side walls of the standard 1 and provided upon one end with a ratchet 32 which is fixed thereto in any usual and well known manner. A spring detent 33 is connected to the adjacent side wall of the standard and engages the ratchet 32 40 to prevent any lost motion thereof.

An operating lever 34 is pivotally mounted upon the shaft 31 and has pivotally mounted thereon at 35 a double pawl 36 provided with the ratchet engaging teeth 37, a spring 45 38 being provided for holding either tooth in engagement with the ratchet when the pawl is thrown over the center by means of the handle 39. A crank 40 may be provided upon the ratchet 32 to be used instead of the 50 operating lever 34 for rotating the shaft 31.

In operating the device when it is desired to lift an object, the seat 13 is placed under the object and the pawl 36 thrown into the position shown in Fig. 3. As the operating 55 lever 34 is oscillated the ratchet will be rotated and through the gears 30 and 29 will rotate the worm 28 in the proper direction to cause the worm rack member 9 of the lifting bar to be slowly raised. When the 60 member 9 has been raised sufficiently to bring the pin 16 into contact with the shoulder 15 of the worm rack member 5, the member 5 will then be raised with the member 9, the worm teeth upon the member 5 being 65 brought into engagement with the worm 28

before the teeth upon the member 9 are moved out of engagement with the said worm.

As the member 5 starts to raise, the locking member 17 will be moved upwardly 70 and inwardly through the inclined grooves 25 projecting the inner end of said locking member beneath the lower extremity of the rack member 9, thus supporting the weight of the rack member 9 upon said locking 75 member and locking the member 9 to the member 5, the pin 16 being thus held in engagement with the shoulder 15 and the member 9 being prevented from movement in either direction with relation to the member 5. Further rotation of the worm 28 will cause the entire lifting bar to be moved upwardly to the upper limit of its movement.

When it is desired to lower the jack the 85 pawl 36 is reversed and the lifting bar is lowered until the rack member 5 is moved downwardly to its lower limit of movement bringing the teeth thereof out of engagement with the worm 28 and bringing the 90 teeth of the rack member 9 into engagement with said worm, the locking member 17 being moved back into the initial position as the studs 24 thereon are again brought into engagement with the inclined grooves 25 in 95 the rear wall of the standard.

I claim:

1. A lifting jack comprising a standard, a lifting bar vertically movable within said standard and comprising two members, lifting means for engagement with both of said members for moving one of said members with relation to the other and means for automatically locking both of said members together at a predetermined point. 100

2. A lifting jack comprising a standard, a lifting bar vertically movable within said standard and comprising two members, lifting means for engagement with both of said members for moving one of said members independently of the other and means for automatically locking said members together when the first member has reached the upper limit of its movement. 110

3. A lifting jack comprising a standard, a lifting bar vertically movable within the standard and comprising a pair of rack members, lifting means for engagement with both of said rack members for moving one of said rack members independently of the other and means for automatically locking said rack members together when the first member has reached the limit of its upward movement with relation to the second member. 120

4. A lifting jack comprising a standard, a lifting bar vertically movable within the standard and comprising a pair of rack members, lifting means for engagement with both of said rack members for moving 130

- one of said rack members independently of the other and means for automatically locking said rack members together when the first member has reached the limit of its upward movement with relation to the second member, and means for moving both of said members after they are locked together. 5
5. A lifting jack comprising a standard, a lifting bar vertically movable within the standard and comprising a channel member and a bar member located therein, lifting means for engagement with the channel member and bar member for moving the bar within the channel, means for automatically locking the bar to the channel when the bar has reached a predetermined point and means for moving the bar and channel together. 10
6. A lifting jack comprising a standard, a lifting bar mounted for vertical movement within the standard and comprising a channel worm rack and a worm rack bar mounted for vertical movement therein, a worm in the standard normally engaging the rack bar, means upon the rack bar for engaging the rack channel to move the same into engagement with the worm and means for automatically locking the rack bar to the rack channel. 15
7. A lifting jack comprising a standard, a lifting bar mounted for vertical movement within the standard and comprising a channel member and a bar member slidably mounted therein, lifting means for engagement with the channel member and bar member for moving the bar member with relation to the channel member, a pin carried by the bar member, a shoulder upon the channel member arranged to be engaged by the pin when the bar member reaches the upward limit of its movement with relation to the channel member and a locking member carried by the channel member and arranged to automatically lock said members together. 20
8. A lifting jack comprising a standard, a lifting bar mounted for vertical movement within the standard and comprising a channel worm rack and a worm rack bar mounted for vertical movement therein, a worm in the standard normally engaging the rack
- bar and normally out of engagement with the rack channel, means upon the rack bar for moving the rack channel into engagement with the worm at a predetermined time and means for locking the rack bar to the rack channel. 25
9. A lifting jack comprising a standard, a lifting bar mounted for vertical movement within the standard and comprising a channel worm rack and a worm rack bar mounted for vertical movement therein, a worm in the standard normally engaging the rack bar and normally out of engagement with the rack channel, a pin upon the rack bar and a shoulder upon the rack channel arranged to be engaged by the pin at a predetermined time to move the rack channel into engagement with the worm and means for locking the rack bar to the rack channel. 30
10. A lifting jack comprising a standard, a lifting bar mounted for vertical movement within the standard and comprising a channel worm rack and a worm rack bar mounted for vertical movement therein, a worm in the standard normally engaging the rack bar and normally out of engagement with the rack channel, a pin upon the rack bar and a shoulder upon the rack channel arranged to be engaged by the pin at a predetermined time to move the rack channel into engagement with the worm, and a locking member carried by the rack channel and arranged to automatically lock the rack bar thereto after the rack channel has been engaged by the worm. 35
11. A lifting jack comprising a standard, a lifting bar vertically movable within said standard and comprising two members, lifting means for engagement with both of said members for moving one of said members upward with relation to the other, means for automatically locking both of said members together at a predetermined time, means for moving both members together, and means for automatically unlocking said members at a predetermined time on the downward movement of the lifting bar. 40
- In testimony that I claim the above, I have hereunto subscribed my name. 45

JOHN A. MORRISON.
